UNITED STATES PATENT OFFICE

123,610

DESIGN FOR A STATIONERY ART BOX

William J. Bargen, Waukegan, Ill.

Application March 13, 1940, Serial No. 90,906

Term of patent 3½ years

To all whom it may concern:

Be it known that I, William J. Bargen, a citizen of the United States, residing at Waukegan, in the county of Lake and State of Illinois, have invented a new, original, and ornamental Design for a Stationery Art Box, of which the following is a specification, reference being had to the accompanying drawing, forming a part thereof.

In the drawing:

I claim:

The ornamental design for a stationery art box, as shown.

WILLIAM J. BARGEN.
